HAROLD E. HOUSEMAN, OF EDGE MOOR, DELAWARE, ASSIGNOR TO STANDARD-TRUMP BROS. MACHINE COMPANY, OF WILMINGTON, DELAWARE, A CORPORATION OF DELAWARE.

PATTERN MECHANISM FOR CIRCULAR-KNITTING MACHINES.

Original application filed November 12, 1926, Serial No. 147,889. Divided and this application filed June 26, 1928. Serial No. 288,321.

In an application filed by me November 12, 1926, Serial No. 147,889, of which this is a division, cam mechanism and needles controlled thereby are adapted to so operate as to produce, in plated fabric containing yarns of different colors, a wide variety of figures or designs, the said cam mechanism being operatively controlled by novel pattern mechanism. In this parent application, 10 the figured effects are produced by so operating certain needles at certain times as to cause them to engage the plating yarn and not the body yarn, thereby causing the latter to float across the fabric; the operation 15 of the needles being controlled by said cam mechanism, which is in turn controlled by said pattern mechanism. The pattern mechanism is not, however, limited in its field of use to the operation or control of any particular cam mechanism; and in an application filed by me July 29, 1927, Serial No. 209,382, the said pattern mechanism has been 20 adapted, with certain inventive modifications, to the actuation of cam mechanism which in turn operates devices to so deflect certain needles at certain times, during the knitting of plated fabric, as to cause the yarns engaged by said needles to be reversed in 25 position and thereby produce reverse plating; the figured effects being thus produced by reversing the positions of the yarns instead of by knitting in one yarn and floating the other. The said pattern mechanism is 30 obviously adapted to control the operation of other mechanism cooperating in other ways in the knitting operation. The subject-matter of this divisional application is the said novel pattern mechanism per se. Such pattern mechanism embodies also features included in a pattern mechanism set forth in 35 an application filed by me May 20, 1926, Serial No. 110,311, and is an improvement or modification thereof and embodies substantially novel features that give the pattern mechanism a different and greater range of 40 utility.

In the parent application, of which this is a division, the novel pattern mechanism was employed to move a single needle actuating cam into a number of different positions. In my said application Serial No. 209,382, the novel pattern mechanism was employed to

selectively operate a number of different needle controlling cams. In the description herein the invention will be illustrated as applied to the movement of a single cam into different operative positions, although it should be clearly understood, from the foregoing, that the invention is not limited in its application to the actuation of any specific mechanism for controlling, or effecting, or cooperating in, the knitting operation.

In the drawings:

Fig. 1 is a plan view of a knitting machine to which the invention has been applied, the figure embodying also a general view of some of the elements of my invention.

Fig. 2 is a side elevation of the parts shown in Fig. 1.

Fig. 3 is a plan view of that part of the machine that embodies my invention.

Fig. 4 is a section through Fig. 3 on the line 4—4, looking in the direction of the arrows.

Fig. 5 is a section on the line 5—5 of Fig. 3, looking in the direction of the arrow.

Figs. 6, 7 and 8 are detail views, in different positions, of the lever mechanism constituting part of my invention.

The cam *g*, whose movement into a number of different positions is effected by the novel pattern mechanism, is held in its innermost position by means of a spring *i* (Fig. 3), which actuates a slide *j* carrying the cam. A bell crank lever *m* engages an adjusting screw *k* on slide *j* and is movable into three different positions to shift the cam *g* into three different positions. The bell crank is moved into and held in three different positions by means of three levers *n*, *n'* and *n''* pivoted on one arm of the bell crank and held against adjusting screws *o* carried by said arm. While spring *g* tends to retract lever *m* from screw *k*, it is ineffective to do so, because levers *n*, *n'* and *n''* are respectively engaged by bell crank levers *r*, *r'* and *r''*, which always engage levers *n*, *n'*, *n''*, respectively. See also Figs. 4—8. Levers *n*, *n'*, *n''* have bevelled ends which are engaged by levers *r*, *r'* and *r''* respectively when cam *g* is in its innermost position. When any lever *r*, *r'*, or *r''* is tilted on its axis, the end contacting with its corresponding lever *n*, *n'* or *n''* rides down beyond the bevelled face

95
100

of the latter and swings it and lever m to retract cam g . Levers n , n' and n^2 do not have their operative faces in the same plane, but in different planes, so that the extent to which lever m is operated depends on which of the levers n , n' and n^2 is operated.

By means of adjusting screws o , one for each lever n , n' , n^2 (only two screws are shown), any departure from exactitude in the shifting of cam g to predetermined distances may be readily corrected.

The movements of the holding levers r , r' , r^2 back and forth are limited by a pin p extending through aligning holes in the levers. Levers r , r' and r^2 are operable respectively by levers t , t' and t^2 , pivoted between their ends on a lever 30, which is reciprocated back and forth, by means to be hereinafter described, as shown by the arrow, Fig. 7. Each lever t , t' and t^2 is held, normally, in the inactive position shown in Fig. 6, against a stop v on lever 30 by means of a spring w .

In Figs. 7 and 8, to avoid confusion, only two sets of levers n and n' , r and r' , t and t' , are shown. In Figs. 4 and 5, all these levers are illustrated.

Each of the levers t , t' and t^2 is actuated by a selector 20, which is movable vertically, by means to be hereinafter described, and as shown in dotted lines in Fig. 4, to selectively actuate any of said levers.

Let it be assumed that cam g is in its innermost position, and that it is desired to move it to another position, and that levers t , r and n are the levers adapted to effect this shift. Selector 20 is moved into alignment with lever t while lever 30 is moving forward (that is, in a downward direction in Figs. 6, 7 and 8). In the backward or upward movement of lever 30, lever t contacts with selector 20 before lever 30 completes its movement, and during the completion of the upward movement of lever 30, selector 20 presses lever t down from its normal position (the upper dotted line position in Fig. 7) to a somewhat lower position (the other dotted line position in Fig. 7), during which limited downward movement of lever t it contacts with the extreme tip of lever r and thereafter snaps over it; the selector 20 (which is held in operative position by a spring 21 that is stronger than spring w) yielding slightly to allow lever t to yield sufficiently to enable it to clear the tip of lever r . Lever 30 now starts to move down, thereby carrying lever t out of contact with the selector. Thereupon spring w tends to restore lever t to its normal position, which movement, if permitted, would prematurely swing lever r into position to actuate lever n . Spring i , however, which is connected, as above described, to slide j , is stronger than spring w , and holds lever r from swinging; and lever r , in turn, acts as a stop to prevent lever t from being actuated by its spring w .

In fact, as lever 30 continues to move down,

lever r has a cam action on lever t and, before the downward movement of lever 30 is completed, lever t is forced against a stop z on lever 30. During the completion of the downward movement of lever 30, lever t is confined between lever r and stop z , and exerts a positive cam action on lever r and tilts it down on its axis, as shown in Fig. 8, thereby swinging lever n into position to swing lever m and shaft cam g .

It should be mentioned that, so far as concerns the operation of the present invention, spring g , acting on lever m , merely supplements the operation of spring i and may be omitted if spring i is made strong enough to perform the functions herein ascribed to it.

In the reverse horizontal movement of lever 30, lever t will release lever r , and if selector 20, in the meanwhile, has been shifted, lever t will be retracted, by its spring w , to the position shown in Fig. 6; but lever r will not be released, because spring i will exert sufficient pressure, through levers m and n , on lever r to hold it in its advanced position. It is desired that lever r shall maintain its advanced position until another chain of levers shall be actuated by the selector, and that lever r shall be retracted at the same time that another lever r' or r^2 is advancing. This is accomplished by causing any of the levers t , t' or t^2 , in the movement by which it advances its corresponding lever r , r' or r^2 , to swing the other levers t and t' , or t and t^2 , or t' and t^2 , into position to retract any of the levers r , r' or r^2 that may be in advanced position.

To make this operation clear, let it be assumed that lever t' has been advanced, that 105 lever 30 is in the down position (Fig. 7), that lever t is in the position shown in Fig. 6, that selector 20 is shifted to align with lever t , that lever 30 moves up, that lever t contacts with the selector and is thereby moved a short distance, that lever 30 starts to move down, that lever t snaps over lever r , and that as lever 30 completes its down movement, lever r is advanced—all as hereinbefore explained. It will be observed, by reference to Fig. 6, that each lever t , t' , t^2 is forked at one end thereof, that stop v acts to limit the movement in one direction of levers t , t' , t^2 by contacting with the lower fork, and that on the shaft carrying levers t , t' and t^2 is pivoted an arm provided with a pin z , which engages the upper fork of any of the levers t , t' , t^2 , that is in its normal position. Assume that, as above described, lever 30 is completing its downward movement and that lever t is swinging from the position shown in Fig. 7 to that shown in Fig. 8. In Fig. 7 it will be observed that the lower fork of lever t has contacted with pin z . Therefore, as lever t swings from the position shown in Fig. 7 to the position shown in Fig. 8, its lower fork 125 actuates pin z . Pin z contacts with the upper 130

forks of the other levers t' and t^2 and swings them into the position in which lever t' is shown in Fig. 8. If, as above assumed, lever r' is in its advanced position, lever t' will 5 contact with lever r' and swing it into the position occupied by lever r' in Fig. 8, thereby causing the end of lever r' to slide onto the bevelled edge of lever n' at the same time that the end of lever r is riding down below 10 the bevelled edge of lever n .

Assume, however, that it is desired to shift cam g to its innermost position. To allow this movement, selector 20 is moved out of alignment with all the levers t , t' , t^2 . Inasmuch as in the next reciprocation of lever 15 30 none of the described sets of levers is operated, it is obvious that the lever r , r' or r^2 that is holding its corresponding lever n , n' , or n^2 , would not be withdrawn from holding 20 position unless some special means were provided for so doing. The operation of withdrawing the lever n , n' or n^2 that is in holding position is, in the assumed case, performed by a special pair of levers 10 and s . 25 Lever 10 has the same construction and operation as any of the levers t , t' , t^2 , and lever s has the same construction and operation as any of the levers r , r' , r^2 ; but inasmuch as lever 10 is ineffective to operate any levers 30 carried by lever m , it is ineffective to effect any shifting of cam g . However, lever s , as it moves from the position occupied by lever t in Fig. 7 to the position occupied by lever t in Fig. 8, acts to tilt levers t , t' and t^2 35 and thereby effect the tilting of any lever r , r' or r^2 that is in holding engagement with its corresponding lever n , n' or n^2 , and thereupon spring i becomes effective to move cam g to its innermost position.

40 Lever 30 is actually the long arm of a bell crank lever pivotally mounted on the machine frame (see Fig. 1). The other arm of this lever has a pin which rides on a cam 51 on gear wheel 50, thereby, in cooperation 45 with a spring 53, giving lever 30 the reciprocating movement hereinbefore described. Gear wheel 50 is geared one to one with the needle cylinder through an intermediate gear 52.

50 Reciprocating lever 30 carries a pawl 32 (see Figs. 1, 3 and 4) that imparts an intermittent progressive movement to a ratchet wheel 33 on the shaft of a pattern chain 35. The pattern chain is provided with removable lugs of four different heights. These lugs are adapted to engage a member 41 carried on a yoke-shaped lever 42 (see Fig 4), on the end of which is mounted the previously described selector 20. The lever 42 is thereby moveable into four different positions, thereby causing the selector to align with any one of the four levers t , t' , t^2 , 10.

It is obvious that by positioning the lugs on the pattern chain, the selector may be shifted to actuate any predetermined chain

of levers at each course of knitting and that thereby cam g may be shifted to cause the needles to be actuated in such manner as to produce any desired pattern.

I have not herein described the means for 70 arresting the movement of the pattern chain during the knitting of the heel and toe, such means forming no part of the present invention but being described in my application Serial No. 110,311 to which reference has 75 hereinbefore been made.

Having now fully described my invention, what I claim and desire to protect by Letters Patent is:

1. In a circular knitting machine, in combination, sets of actuatable mechanism, actuating means for the respective sets of mechanism adapted to move them in one direction, pattern-controlled means adapted to selectively render any of said sets of mechanism 80 effectively so movable by its actuating means, and means operable by any of said sets of mechanism to control the movement in the opposite direction of any other set of mechanism that is so movable. 90

2. In a circular knitting machine, pattern mechanism comprising a plurality of shifting levers, mechanism which is differentially operable by the respective shifting levers, a plurality of operating levers one for each 95 shifting lever, and connecting means operable, when any operating lever is rendered operative, to synchronously put into operation its shifting lever and render inoperative any other shifting lever which had been previously rendered operative. 100

3. In a circular knitting machine, in combination, a plurality of chains of levers, a reciprocatory member carrying the lever of each chain that is adapted to advance a 105 second lever of the same chain, means to actuate the reciprocatory member, pattern-controlled mechanism adapted to selectively render operative the first lever of a chain, and means, operable by each of said first 110 levers, in its movement to actuate a second lever of the same chain, to so actuate the first levers of the other chains that any of the second levers that is advanced will be retracted by its actuating first lever. 115

4. In a circular knitting machine, pattern mechanism comprising a set of actuatable levers, a corresponding set of actuating levers normally inoperative to actuate their corresponding actuatable levers, selecting means 120 adapted to render any one of said actuating levers operative to move its corresponding actuatable lever, and connections between said actuating levers whereby when any one is positioned by the selecting means to move 125 its actuatable lever in one direction the other actuating levers are positioned to move in the opposite direction any corresponding actuatable levers which are in position to be so moved. 130

5. In a circular knitting machine, pattern mechanism comprising actuatable levers, a set of actuating levers, one for each of the actuatable levers, adapted to move their corresponding actuatable levers in either direction, selecting means adapted to render any one of the actuating levers active to move its corresponding actuatable lever in one direction, and connecting means operable, when any actuating lever is rendered operative, to cause the other operating levers to move in the opposite direction any corresponding actuatable levers which are in position to be so moved.
15. 6. In a circular knitting machine, the combination with mechanism adapted to cooperate in the knitting operation and to be differentially operated, of a plurality of chains of levers adapted to actuate said mechanism to impart differential movements thereto, another special chain of levers disconnected from said mechanism, pattern means adapted to selectively actuate the several chains of levers, and means, operable by any of the 25 chains of levers when so selectively actuated, to control the movement out of actuating position of any other of the first named plurality of chains of levers that is in actuating position, whereby the selective actuation of the special chain of levers renders said mechanism inoperative by any chain of levers.
30. 7. In a circular knitting machine, pattern mechanism comprising a reciprocating member, a set of levers carried thereby, a second set of levers which are respectively actuatable by the levers of the first set, a third set of levers which are respectively actuatable by the levers of the second set, the corresponding first, second and third levers of different 35 sets constituting a chain of levers, pattern-controlled selecting means adapted to be positioned, while the reciprocating member is moving in one direction, to move one of the first levers toward its actuating position, said first lever being movable, in the reverse 40 movement of the reciprocating member, to so actuate the second lever of the same chain as to effect the actuation of the third lever of the same chain.

8. The pattern mechanism set forth in claim 7 comprising also a spring tending to retract the first lever after it recedes from the selecting means during the reverse movement of the reciprocating member, the second lever of the same chain acting as a stop to prevent said retraction and moving said first lever into actuating position, said first lever operating, in the further reverse movement of said reciprocating member, to positively so actuate said second lever as to effect the actuation of the third lever of the same chain.

9. The pattern mechanism set forth in claim 7 comprising also a cam on said second lever adapted to move said first lever into actuating position before said reverse movement of said reciprocating member is completed, the further reverse movement of said reciprocating member effecting a positive actuation of said second lever by said first lever.

10. The pattern mechanism set forth in claim 7 comprising also means, operable by said first lever, during its actuation of said second lever, to so move the first levers of the other chains that the second lever corresponding to the third lever of any other chain that is in operative position will be retracted from the position required to maintain the last named third lever in operative position.

11. The pattern mechanism set forth in claim 7 comprising also a special chain of two levers corresponding respectively to the first and second levers of the other chains, and means, operable by the first lever of any chain, during its actuation of the second lever of the same chain, to so move the first levers of the other chains that the second lever corresponding to the third lever of any other chain that is in operative position will be retracted from the position required to maintain the last named lever in operative position.

In testimony of which invention, I have hereunto set my hand, at Philadelphia, Pennsylvania, on this 13th day of June, 1928.

HAROLD E. HOUSEMAN.
